TRAY FOR SYRINGES OR THE LIKE

Robert B. Jenkins, P.O. Box 1160, Gastonia, N.C.

Filed Nov. 5, 1959, Ser. No. 58,221

Term of patent 14 years

(Cl. D83—1)

FIGURE 1 is a perspective view of a tray for syringes or the like embodying my new design;

The dotted line showing of the syringe and card in FIGURE 1 is for illustrative environmental purposes only.

I claim:

The ornamental design for a tray for syringes or the like, substantially as shown and described.
